APPARATUS FOR STEPPING UP DIRECT-CURRENT VOLTAGE

Charles C. Shumard, Moorestown, N. J., assignor to Radio Corporation of America, a corporation of Delaware

Application March 30, 1948, Serial No. 17,959

6 Claims. (Cl. 171—97)

1

This invention relates to apparatus for obtaining a high D.-C. voltage from a lower voltage D.-C. source. More particularly, the invention relates to apparatus comprising a number of interconnected gas discharge tube circuits including capacitors for raising the level of D.-C. voltage output from a low voltage D.-C. source, which voltage increase is made at the expense of a lowering in output current.

Previous to the present invention, various types of circuits have been devised for stepping up D.-C. voltage. Some, such as shown in U. S. Patent 2,074,495, include circuits for both rectifying an A.-C. voltage and stepping up the value of the voltage above the original A.-C. level by utilizing the high voltage output effect of the sudden collapse of flux in an inductance coil. Another type of circuit is shown in U. S. Patent 1,938,209. Here, the low voltage D.-C. current is first converted to A.-C., which is stepped up to higher voltage A.-C. and then rectified.

The present invention differs from both of the above types of prior art devices. The voltage source used is a low voltage D.-C. source and the rise in voltage is obtained by converting the D.-C. voltage directly to a higher voltage A.-C. and then rectifying to D.-C. at the same high voltage level. In the present invention, the D.-C. voltage rise is due to successive increases in effective operating capacitor voltages obtained from alternately exciting series resonant circuits and, as an additional feature, to the unsymmetrical use of the resonant circuits.

A principal object of the present invention is to provide an improved apparatus for obtaining a high D.-C. voltage from a low voltage D.-C. source.

Another object of the invention is to provide a transformerless means for stepping up D.-C. voltage, which is simple in structure and in operation.

Another object of the invention is to provide an apparatus for stepping up D.-C. voltage, which is easily adaptable to use with presently existing sources of low D.-C. voltage, and which is capable of raising the voltage to a level required by apparatus such as television kinescopes.

Still another object of the invention is to provide an improved apparatus for stepping up D.-C. voltage, which apparatus is easily adapted to cover a broad range of operation by merely adjusting the circuit constants.

These and other objects will be more apparent and the invention will be more readily understood

2

from the specification and the illustrative drawings, of which:

Fig. 1 is a schematic diagram of one embodiment of apparatus constructed in accordance with the present invention.

Fig. 2 is a schematic diagram of part of the circuit of Fig. 1 and has been included only for the purpose of aiding in the illustration of the derivation of suitable circuit constants for the circuit of

Fig. 1,

Fig. 3a is a typical wave output of voltage that can be obtained from the circuit of Fig. 1 when symmetrical bias is used for the gas discharge tubes, and

Fig. 3b is a voltage wave output similar to Fig. 3a except that unsymmetrical bias is used.

Referring now to Fig. 1, it will be evident that the embodiment of the improved apparatus shown therein is comprised primarily of three circuit meshes. One of these, which may be termed mesh 1, includes a low voltage supply E_b , an inductor L_1 , having an inherent series resistance R_{L_1} , a thyratron tube V_1 , a capacitor C_1 and the parallel combination of a capacitor C_2 and resistor R_{C_2} , all in series. Another mesh, which may be termed mesh 2, comprises the capacitor C_1 , the parallel combination of a capacitor C_3 and resistor R_{C_3} , an inductor L_2 having an inherent series resistance R_{L_2} and a thyratron tube V_2 , all of which elements are in series. The third mesh, which may be termed mesh 3, comprises a rectifier diode tube V_3 in series with the parallel combination of a capacitor C_4 and resistor R_{C_4} , another parallel combination comprising the capacitor C_2 and resistor R_{C_2} , and the capacitor C_1 .

The grid of tube V_1 is provided with a grid leak resistor R_{G_1} , one end of which is connected between the junction of the capacitor-resistor combination $C_3-R_{C_3}$ and the inductor L_2 . The grid of tube V_2 is provided with a grid leak resistor R_{G_2} , one end of which is connected to ground.

It will be seen that the capacitor C_1 is common to all three meshes of the circuit and that the parallel capacitor-resistor combination $C_2-R_{C_2}$ is common to circuit meshes 1 and 3. The rectifier tube V_3 serves only to rectify A.-C. voltages appearing across that portion of the circuit to which it is connected.

The general principle of operation of the improved apparatus of the invention will first be explained by reference to the simplified diagram of Fig. 2. In this simplified diagram, the rectifier tube V_3 has been omitted. With the rectifier tube omitted, the circuit meshes reduce to mesh 1 and mesh 2, each of which includes a gas discharge

55

thyatron tube V_1 and V_2 , respectively. These thyatrtons may be considered as single-pole, single-throw switches but allowing, however, conventional current to flow, when closed, only in one direction—that from anode to cathode, in each case.

With no original charge on capacitor C_1 , the low voltage supply E_b may be applied to mesh 1 by closing switch S . Tube V_1 will begin conducting immediately since capacitor C_3 is not charged and, hence, no grid bias voltage is at first available for this tube. The capacitors C_1 and C_2 will, therefore, immediately begin to charge. Since the junction between the capacitors C_1 and C_2 is connected to the cathode of tube V_2 , the positive anode-to-cathode voltage of tube V_2 will be provided by the voltage to which capacitor C_1 becomes charged and a negative grid-to-cathode voltage will be provided by the voltage to which capacitor C_2 becomes charged. If the values of the capacitors C_1 and C_2 and of the resistor R_{C_2} are properly selected, the tube V_2 will not conduct when current flows in mesh 1.

Current will continue to flow in mesh 1 only until capacitor C_1 is fully charged, at which time the current would normally tend to reverse its direction but it cannot do so since the tube V_1 is a unilateral conductor. The current, therefore, becomes zero and the voltage across the inductor L_1 collapses leaving capacitor C_1 fully charged to a voltage which depends upon the circuit constants of circuit mesh 1. This residual voltage may be made by the proper choice of these constants to exceed the plate supply voltage E_b so that the cathode of tube V_1 is left momentarily positive with respect to its anode. It will, therefore, start to deionize at this time.

The residual voltage constitutes the anode-cathode voltage of tube V_2 but tube V_2 will not begin to conduct until its grid bias voltage, which consists of the voltage across capacitor C_2 , has decreased through the agency of the resistor R_{C_2} to a value insufficient to maintain tube V_2 in a non-conducting state. When tube V_2 does suddenly begin conducting, capacitor C_1 begins discharging through circuit mesh 2, charging capacitor C_3 and establishing a negative grid-to-cathode voltage on tube V_1 before the cathode of this tube becomes negative with respect to its anode. Thus, if the bias on tube V_2 is maintained until tube V_1 has deionized, tube V_1 will not reconduct when tube V_2 becomes conducting.

Capacitor C_1 will continue to discharge and charge to a voltage of opposite polarity but of lesser amplitude, the amplitude being less by the amount of the tube drop and dependent otherwise on the circuit constants of mesh 2. When this voltage is of maximum amplitude, the current would again normally reverse its direction. But since the thyatron V_2 is also a unilateral conductor, the current cannot reverse and so decreases to zero. The voltage across the inductor L_2 collapses, leaving capacitor C_1 charged to the above stated maximum value, the anode of tube V_2 being left negative with respect to its cathode. The tube V_2 will, therefore, start to deionize.

The anode-to-cathode voltage now existing on tube V_1 is the sum of two voltages, of which (1) is that provided by the low voltage supply E_b and (2) is the residual voltage on capacitor C_1 . The tube V_1 will conduct again as soon as the negative grid-to-cathode voltage, provided by the voltage across the capacitor C_3 , is permitted to drop to a low enough value through the medium

of the leak resistor R_{C_2} . The capacitor C_1 will then discharge from its previous state of negative charge with respect to ground and charge to a positive value with respect to ground in a manner similar to that when the switch S was first closed, with the difference that its second maximum value will be substantially higher than its first maximum value. Also, the voltage across the capacitor C_2 will now be greater, thus providing higher negative grid bias for tube V_2 . Thus, it is noted that positive anode-to-cathode voltages and the negative grid-to-cathode voltages will be proportionally higher. Similarly, higher voltages will be produced after the tube V_2 again conducts. From this, it can be seen that the voltages build up during the transient state to limiting values which are determined by the constants of the circuit meshes 1 and 2.

For proper operation of the above described circuit, suitable circuit constants must be chosen. Meshes 1 and 2 may have, but are not limited to, identical circuit parameters. In practical operation, the value of capacitor C_1 is usually small compared to the values of capacitors C_2 or C_3 since it is desired to have the voltage across capacitor C_1 quite large compared to the bias voltages appearing across capacitors C_2 or C_3 . Moreover, it is desired to have the effective series resistance small, which requires for a given time constant $C_2-R_{C_2}$ that C_2 be large and R_{C_2} small. For practical design, then, an effective series resistance value is used in series with the capacitor to be also common to both meshes 1 and 2, which is the sum of all the effective resistances around mesh 1 and/or mesh 2; C_2 or C_3 is considered large compared to the value of C_1 , and L_1 is generally made equal to L_2 .

Having described the principles of operation of the simplified circuit of Fig. 2, the operation of the complete apparatus will now be described with reference to Fig. 1.

With the rectifier diode tube V_3 inserted, the circuit of mesh 3 is completed. When, therefore, the capacitor C_1 becomes positive with respect to ground, current may flow through the rectifier tube V_3 , charging capacitor C_4 . If resistor R_{C_4} has a very high value, or is open, the maximum voltage appearing on the capacitor C_4 will be substantially the maximum positive value which capacitor C_1 attains (except for the drop in the tube V_3). This voltage will be retained on the capacitor C_4 when the polarity on capacitor C_1 reverses, since tube V_3 is a unilateral conductor. The capacitor C_4 would take no further charge after being charged initially, if load current were not being drawn through load resistor R_{C_4} . However, when load current is being drawn through resistor R_{C_4} , if the current drawn by it is not excessive, the capacitor C_4 will be recharged every time that capacitor C_1 approaches and assumes its maximum positive value. The load output is, therefore, seen to comprise the rectified output of the alternating voltage appearing across the capacitor C_1 .

Obviously, the current drawn by the load resistor R_{C_4} must be less than the value which would be indicated by dividing the current supplied by the low voltage supply by the step-up voltage ratio, since there are some losses. The wave shape and hum content depend on the ratio of resistance R_{C_4} to the value of capacitor C_4 . For smaller load currents, the average D.-C. output voltage closely approaches the peak positive voltage appearing across capacitor C_1 . Conversely, the greater the load current the less the

voltage appearing across capacitor C_1 , since the effective series resistance is ultimately greatly affected and may finally result in an inoperative condition. For no load, the value of capacitor C_4 will not affect steady state operation.

The grid leak resistors R_{G_1} and R_{G_2} , of a few thousand ohms each, serve the double purpose of limiting grid current flow in the tubes V_1 and V_2 , respectively, and regulating the time of discharge of capacitors C_2 and C_3 , respectively.

Although the mode of operation of the apparatus has been described whereby there is obtained a stepped up positive D.-C. voltage, the apparatus may obviously be easily modified such that the voltage across capacitor C_1 could be rectified to obtain a high negative D.-C. voltage. This is done by reversing the connections of the rectifier tube V_3 . The relative voltage output, however, would always be lower than in the case of a positive voltage.

The D.-C. positive voltage output of mesh 3 may be raised by the use of longer time constants for the combination capacitor-resistor $C_3-R_{C_3}$ or shorter ones for the combination $C_2-R_{C_2}$ since this allows the charge on capacitor C_1 to remain for a longer time after this capacitor has been charged to its maximum positive value. The process may be reversed, however, to equalize the forward and reverse voltages, if required.

Circuit values will now be given for apparatus capable of raising D.-C. voltages of about 30-60 to D.-C. voltages of about 100-300.

In all cases, in the following examples:

$L_1=L_2=55$ millihenries.
 $C_1=0.25\ \mu f.$; $C_4=0.05\ \mu f.$; $R_{C_4}=1$ megohm;
 $R_{G_1}=R_{G_2}=5,000$ ohms.
 V_1 and V_2 may be type 884 thyratron tubes.
 V_3 may be a 5Y3GT, using plates in parallel.

Example 1

For a symmetrical bias circuit in which $C_2=C_3=25\ \mu f.$, and $R_{C_2}=R_{C_3}=220$ ohms:

E_b (volts) -----	26	40	50	60
D.-C. output (volts) -----	100	165	205	250

Frequency of operation=84 cycles with 58 v. peak to peak ripple voltage. The voltage across capacitor C_1 consisted of two equally spaced, approximately square wave-forms. The wave-form of the D.-C. output appeared as shown in Fig. 3a.

Example 2

For an unsymmetrical bias circuit in which $C_2=C_3=25\ \mu f.$; $R_{C_2}=68.8$ ohms and $R_{C_3}=330$ ohms:

Frequency of operation was 78 cycles. When E_b was 60 volts, the D.-C. output was 280 volts (an increase in voltage of 30 over the comparable voltage output of Example 1). At the same time, the ripple voltage decreased to 33 v., peak-to-peak. This is due to holding the capacitor C_1 at its positive value for a longer time by the longer time constant $C_3-R_{C_3}$ and the shorter time constant $C_2-R_{C_2}$. Capacitor C_1 then aids in the filtering and raises the rectified voltage value. The wave-form of the rectified D.-C. voltage and the wave-shape of the voltage across capacitor C_1 is shown in Fig. 3b.

It is obvious that in the above circuits higher values of D.-C. output voltage may be obtained when higher D.-C. supply voltages E_b are used. It is also apparent that considerably higher D.-C. output voltages may be obtained from voltages such as illustrated in the examples, by proper

choice of circuit constants. A particularly useful form of the invention is one having circuit values which will permit the raising of a D.-C. supply of about 300 to that required for a kinescope. For this practical application, the circuits of the present invention offer improved means for obtaining a high D.-C. voltage at low current. Most power supplies of previous design have offered considerable power capacity but relatively low voltage output.

There has thus been described an improved apparatus for raising the voltage normally obtained from low level D.-C. sources to considerably higher values. The circuit components are few and may be arranged to form a compact unit. Although but a single embodiment of the invention has been shown in the drawings, it will be understood that various modifications may be made without departing from the spirit of the invention. For example, rectifying means, other than a diode tube, may be used and many different combinations of circuit constants may be selected. It is desired that the invention be limited only as indicated by the scope of the appended claims.

I claim as my invention:

1. Apparatus for deriving a raised D.-C. voltage from a low voltage D.-C. source, said apparatus comprising a capacitor, means for alternately charging said capacitor in one direction from said source to a voltage level higher than that of said source and for discharging said capacitor and charging it in the opposite direction, and means for deriving a unidirectional voltage from the voltage appearing across said capacitor.
2. Apparatus for deriving a raised D.-C. voltage from a low voltage D.-C. source, said apparatus comprising a capacitor and means for applying the voltage from said source so as to charge said capacitor in one direction to a voltage level higher than that of said source, means for disconnecting said capacitor from said source and for discharging said capacitor and charging it in the opposite direction, and means for deriving a unidirectional voltage from the voltage appearing across said capacitor.
3. Apparatus for deriving a high D.-C. voltage from a low voltage D.-C. source having a certain voltage level, said apparatus comprising a first circuit mesh including a first gas discharge tube and a capacitor and means for applying the voltage from said source to charge said capacitor in one direction when current is flowing in said first tube, a second circuit mesh including said capacitor, a second gas discharge tube and means for preventing said first tube from conducting while said second tube is conducting, said second circuit mesh being connected so as to discharge said capacitor through said second circuit mesh during periods when said second tube is conducting whereby said capacitor becomes charged in the opposite direction, means for rendering said second tube conducting when said capacitor has become charged to a predetermined value in said one direction, means for rectifying the voltages appearing across said capacitor, and means for applying said rectified voltage to a load circuit.

4. Apparatus for deriving a raised D.-C. voltage output from a low voltage D.-C. source, said apparatus comprising a first circuit mesh including a gas discharge tube, a capacitor and means for applying the voltage from said source through said tube so as to charge said capacitor in one direction, a second circuit mesh including said

7
 capacitor, a second gas discharge tube and means for preventing said first tube conducting while said second tube is conducting, means in said first circuit mesh for preventing said second tube conducting while said first tube is conducting, means for rendering said second tube conducting when said capacitor has become charged to a predetermined value in said one direction, means for discharging said capacitor through said second circuit mesh during periods when said second tube is conducting, whereby said capacitor becomes charged in the opposite direction, and means for deriving a unidirectional voltage from the voltage appearing across said capacitor.

5
 10
 15
 5. Apparatus according to claim 4 in which said means for deriving a unidirectional voltage comprises rectifying means connected across said capacitor.

6. Apparatus for deriving a raised D.-C. voltage from a low voltage D.-C. source, said apparatus comprising a first circuit mesh including said source, a first gas discharge tube and a capacitor, said first discharge tube being connected so as to charge said capacitor in one direction when
